(57) CLAIM

I claim the ornamental design for a funeral flag, as shown and described.

DESCRIPTION

FIG. 1 is a perspective view of a funeral flag showing my new design;

FIG. 2 is a front elevational view thereof;

FIG. 3 is a rear elevational view thereof; and,

FIG. 4 is a top plan view thereof, the bottom plan view being identical thereto.

1 Claim, 3 Drawing Sheets

FIG. 3.
